CLAIM

The ornamental design for a connection adapter for a quick-connect, as shown and described.

DESCRIPTION

FIG. 1 is a perspective view of a connection adapter for a quick-connect in accordance with the new design;

FIG. 2 is a left side view of the connection adapter for a quick connect of FIG. 1;

FIG. 3 is a right side view of the connection adapter for a quick connect of FIG. 1;

FIG. 4 is a front view of the connection adapter for a quick connect of FIG. 1;

FIG. 5 is a rear view of the connection adapter for a quick connect of FIG. 1;

FIG. 6 is a top view of the connection adapter for a quick connect of FIG. 1; and,

FIG. 7 is a bottom view of the connection adapter for a quick connect of FIG. 1;

In the drawings, the broken lines shown in FIGS. 1-5 and 7 illustrate portions of the connection adapter for a quick connect that form no part of the claimed design.

1 Claim, 7 Drawing Sheets
